**PIN CORE STRUCTURE FOR DECREASED
CHECKING**

Fred E. Satchell, and Foster W. Berry, Muskegon, Mich.,
assignors to Brunswick Corporation, a corporation of
Delaware

Filed Oct. 15, 1962, Ser. No. 230,476
5 Claims. (Cl. 273—82)

This invention relates to bowling pins and more particularly relates to preventing or inhibiting neck checking in wood core bowling pins.

Bowling pins used in such games as ten pins and duck pins are subjected during use to high stresses generated by impact by a bowling ball with the pin. Such high stresses are particularly prominent at or just below the minimum section of the pin, i.e., in the neck region of the pin. The high stresses, together with the natural configuration of the tissue elements of a wood core, may often result in "checking" or failure in the wood core parallel to the wood grains. Such checking may be engendered by repeated impact during use of the pin, or even by a single hard blow. Such checking may occur almost anywhere along the length of the pin although the neck section, especially at or below the minimum diameter of the pin, is often the most vulnerable site for check origination. Once the checks or splitting failures have been started in a pin, their growth or extension into other parts of the pin results in complete failure of the pin. Failure of pins due to checking is currently a serious problem and constitutes a prominent cause of shortened pin life.

It is a general object of this invention to provide a new and useful bowling pin having reduced checking tendencies.

More particularly, it is an object of this invention to provide a new and useful bowling pin including an internal elastic or elastomeric material, especially in the neck region of the pin, which serves to reduce the tendency of check formation in the outer wood surface of the pin core.

It is a further object of this invention to provide a bowling pin which has a core structure including a plurality of wood portions and a substantially internal elastic body of elastic material between the wood portions, at least in the neck section of the pin.

It is another object of this invention to provide such a bowling pin wherein the wood portions of the neck region of the pin include a plurality of separate hardwood portions bonded to a continuous substantially internal elastic matrix of elastomeric material having a substantially lower modulus of elasticity than the modulus of elasticity of the hardwood.

In one embodiment of the present invention there is provided a bowling pin in accordance with the foregoing objects in which the core consists essentially of a plurality of elongated wood blocks with the matrix or elastomeric material interposed therebetween, the blocks and matrix extending the length of the wood core.

In still another embodiment of this invention there is provided a bowling pin in accordance with the above objects wherein the wood portions of the core comprise a base-belly-shoulder portion having a receptacle in its upper surface and a head-neck portion having a projection from its lower surface, the projection being received within the receptacle and spaced from the walls of the receptacle and the internal matrix of elastomeric material being coincident with the space between the projection and the walls of the receptacle.

Other objects and embodiments, including the use of a synthetic rubber material such as thiokol rubber as the elastic or elastomeric material, the use of particular thicknesses of such elastic or elastomeric material, and

2

still other objects will be apparent from the following descriptions and drawings in which:

FIG. 1 is a vertical section of an embodiment of the bowling pin of this invention, corresponding to a section taken along lines 1—1 of FIG. 2;

FIG. 2 is a horizontal section through the embodiment illustrated in FIG. 1 along lines 2—2 of FIG. 1;

FIG. 3 is a vertical section through another embodiment of the bowling pin of this invention; and

FIG. 4 is a horizontal section through the embodiment illustrated in FIG. 3 taken along lines 4—4 of FIG. 3.

While this invention is susceptible of embodiment in many different forms, there is shown in the drawings and will herein be described in detail an embodiment of the invention together with a modification thereof with the understanding that the present disclosure is to be construed as an exemplification of the principles of the invention and is not intended to limit the invention to the embodiments illustrated. The scope of the invention will be pointed out in the appended claims.

Referring first to FIGS. 1 and 2 of the drawings there is illustrated an embodiment of the bowling pin of the present invention. Pin core 10 is formed of laminated maple blocks 11, 12, 13 and 14, elongated maple blocks lettered *a* through *r*, and a thiokol rubber longitudinal elastic member or matrix 15. Although the longitudinal matrix illustrated includes, in the horizontal cross-sectional view of FIG. 2, individual element thicknesses of $\frac{1}{4}$ to $\frac{3}{8}$ inch effectively extending substantially across the core, other thicknesses and configurations in the matrix may be used as will be apparent. Blocks *a* through *r* are bonded to matrix 15. Additionally the peripheral blocks of the plurality of elongated blocks *a* through *r* are laminated to blocks 11, 12, 13 and 14 in the core structure. Matrix 15 is bonded to all wood blocks in contact therewith. An ethylcellulose lacquer coating 16 is provided on the exterior of core 10 and the coated core comprises a regulation size ten pins bowling pin. Of course, other adaptations such as an impact resistant base may be incorporated in the illustrated pin.

Although the pin core is described as formed of laminated maple blocks, other woods, and especially other hardwoods, may be used. Also, other coating materials, either in combination with or in lieu of ethylcellulose, may be used, including nitrocellulose, cellulose acetate, cellulose acetate and butylate, epoxies, urethanes, and the like. Such coating materials are well known to those in the art.

Referring now to FIGS. 3 and 4, there is illustrated another embodiment of the present invention. In FIGS. 3 and 4, core 20 is constructed of an upper or cap-head-neck portion 21 and a lower or base-belly-shoulder portion 22. Upper portion 21 includes projection 23 at the lower end thereof and lower portion 22 includes receptacle 24 at the upper end thereof. Projection 23 and receptacle 24 are positioned in spaced relation to each other, i.e., the walls of receptacle 24 being spaced from the walls of projection 23. Filling the space between projection 23 and receptacle 24 is a thiokol rubber transverse member or cup 25 which has a wall and bottom thickness, as illustrated, of about $\frac{1}{4}$ to $\frac{1}{2}$ inch. A coating 26 of ethylcellulose or other coating material is provided on the surface of core 20.

Although the embodiments of FIGS. 1 through 4 have been described as employing thiokol rubber as the elastic material, it is to be understood that other materials which are highly elastic may be used. The elastic material of the internal elastic body of the bowling pin of this invention has a substantially lower modulus of elasticity than that of the wood of the core. Both natural and synthetic rubber-like materials are usable, for example, including natural rubber, chemically resistant rubber such as thiokol

or polysulfide rubber, copolymers of styrene and butadiene such as GR-S rubber, polybutadienes such as Buna rubber, cold-flow rubber (polyisobutylene), butyl rubber (a copolymer of isobutylene with small amounts of butadiene), polychloroprene such as neoprene, silicone rubber (e.g. polydimethylsilanol), polyurethane rubber, and the like. The elastic or elastomeric material has a lower tensile strength than that of the wood of the core. Any elastic or rubber-like material is usable.

The elastic material can be used in any configuration within the wood core pin when viewed in horizontal section, e.g. triangular, parallel line, circular, radial, etc., configuration. The location of the elastic material is not critical so long as it constitutes an elastic body of material separating a plurality of, i.e. at least two, pieces of wood in the core. It is preferred, however, that the elastic material be sufficiently toward the center of the pin at the belly portion of the pin, if it is present at the belly portion, to permit sufficient circumferential wood at the belly to maintain good playing characteristics.

The thickness of the elastic material depends somewhat on the elasticity of the material. As the elasticity of the material increases, it can be used in lesser thicknesses. For more advantageous use of elastic materials, the individual elements of elastic material in the core should be at least 5 to 10 mils in thickness even where very soft and elastic materials are used. When using the soft and yielding materials of soft rubber consistency, it is preferred that they be included in the core of the pin in a thickness of at least about 60 mils.

Although, as indicated above, one elastic element may be provided between two wood core members in accordance herewith, because the elastic elements are free to deflect in shear, increasing their number gives a greater cushioning effect to the pin core, thus, cushioning depends on at least the elasticity of the material and the thickness and number of elastic elements. The cushioning effect is accordingly adjustable by increasing the elasticity and/or thickness or number of elastic elements used to increase cushioning, or by decreasing the elasticity and/or thickness or number of elements to decrease the cushioning effect. This permits adjusting of the cushioning effect in both directions so that checking of the core may be lessened or prevented; but if the resulting cushioning effect of a certain elastic material or thickness of material in a given pin construction results in an undesirably over-cushioned or sound "deadened" pin, the cushioning effect may be readjusted in subsequently produced pins of that construction to regain at least some of the sound characteristics.

The manufacture of bowling pins in accordance herewith includes generally the lamination and shaping of a wood core containing the elastic member and thereafter coating the shaped core. The elastic member may be included in the core by introducing the elastic material in a liquid state, i.e. molten, plasticized, unpolymerized or as a solution into the spaces between the wood core elements. Accordingly, a bowling pin of the configuration of that in FIG. 1 can be formed by first forming a mold cavity by laminating blocks 11, 12, 13 and 14 together, supporting blocks *a* through *r* within the cavity and pouring liquid elastic material, e.g. thiokol rubber, into the cavity surrounding the elongated wood blocks. The elastic material is then cured in place. For curing, some elastic materials may require heat and/or pressure and because of the difficulties in applying pressure to the mold cavity it is preferred that the elastic material be one curable without application of pressure.

In like manner, a pin of the configuration illustrated in FIGS. 3 and 4 may be made by turning blocks 21 and 22 separately, placing thiokol rubber within cup 24, and inserting projection 23 into cup 24 causing the thiokol rubber to flow upward and fill the space between projection 23 and the walls of cup 24. Thereafter, the thiokol rubber is cured. In either case the wood blocks may be pre-

shaped, if desired, or preferably the resulting built-up core is shaped to its proper size and configuration for coating to form a finished bowling pin.

Alternatively, the elastic body may be molded separately from the pin, e.g. in the shape of longitudinal member 15 or transverse member 25, and thereafter laminated between the respective wood portions of the pins using a suitable adhesive material. Suitable adhesive materials are well known to those in the art; for example, an epoxy resin adhesive may be used to bond a molded thiokol rubber elastic member to maple wood portions of the bowling pin core.

After the core has been formed, the coating material is applied by any of a variety of well known processes including dipping, brushing, flowing, etc.

It is evident from the foregoing that the present invention provides new and useful bowling pins which may include a predominately wood core with a substantially internal elastic body of material between wood portions of the core. The pins provided in accordance herewith, when subjected to normal bowling use, are less susceptible to neck checking than are the wood core bowling pins not including the elastic body. Such prevention or inhibition of neck checking in bowling pins often results in extended playing life of the pins, reducing the frequency of their replacement.

We claim:

1. A bowling pin comprising an upper wood portion, a lower wood portion and a transverse continuous substantially internal elastic body of elastic material between said upper and lower portions and bonding said upper and lower portions, said transverse body being between the largest and smallest diameters of said pin, said elastic material being of sufficient mass to decrease checking of the surface wood in the neck of the pin normally caused by impact at the belly of the pin.

2. A bowling pin comprising a predominately wood core having a neck portion consisting essentially of a plurality of separate hardwood portions bonded to a continuous substantially internal elastic matrix of elastomeric material having a substantially lower modulus of elasticity than said wood, said wood portions comprising a base, belly and shoulder portion having a receptacle in its upper surface and a head and neck portion having a projection from its lower surface received within said receptacle in spaced relation to the walls of said receptacle and said internal matrix being coincident with the space between said projection and the walls of said receptacle.

3. A bowling pin having a core including a neck portion and a belly portion and comprising a plurality of wood portions and a substantially internal elastic body of elastic material extending the length of said core between said wood portions for absorbing sufficient shock to reduce neck checking in the pin under impact of the pin in the belly portion by a bowling ball.

4. A bowling pin having a predominately wood core including a neck portion and a belly portion and comprising a plurality of elongated separate hardwood portions and a continuous substantially internal elastic matrix of elastomeric material extending the length of the core for absorbing sufficient shock to reduce neck checking in the pin under impact of the pin in the belly portion by a bowling ball and for bonding said hardwood portions in spaced relation, said elastomeric material having a substantially lower modulus of elasticity than the wood.

5. A bowling pin having a solid core comprising a plurality of spaced elongate wood blocks each extending the length of the core and a continuous substantially internal elastic body of elastic material having a substantially lower modulus of elasticity than that of said wood, said internal body of elastic material extending the length of the core and being of a thickness greater than about 5-10 mils for permitting flexure of said wood blocks relative to each other and absorbing sufficient shock from impacts in the belly portion of the core by a

bowling ball to reduce neck checking in the pin, said core including an amount of wood sufficient to maintain the playing sound characteristics of a wood pin, and said wood blocks being bonded and held by said elastic body of elastic material.
